UNITED STATES PATENT OFFICE

156,663

CAKE MOLD

James Renalde, Denver, Colo.

Application August 16, 1948, Serial No. 148,139

Term of patent 3½ years

(Cl. D44—29)

To all whom it may concern:

Be it known, that I, James Renalde, a citizen of the United States of America, residing at Denver, in the county of Denver and State of Colorado, have invented a new, original, and ornamental Design for a Cake Mold, of which the following is a specification, reference being had to the accompanying drawing, forming part thereof.

In the drawing:

Fig. 1 is a front view of a cake mold, showing the new design;

Fig. 2 is a back view thereof; and

Fig. 3 is a side view thereof.

I claim:

The ornamental design for a cake mold, as shown.
